UNITED STATES PATENT OFFICE.

JOSEPH SILVERMAN, OF CHICAGO, ILLINOIS.

DESIGN FOR A CHAIR-BACK.

No. 38,279.

Specification for Design.

Patented Oct. 9, 1906.

Application filed August 21, 1906. Serial No. 331,535. Term of patent 14 years.

To all whom it may concern:

Be it known that I, JOSEPH SILVERMAN, a citizen of the United States, residing at Chicago, in the county of Cook and State of Illinois, have invented a new, original, and ornamental Design for Chair-Backs, of which the following is a specification, reference being made to the accompanying drawing, forming a part thereof.

The figure is a face view of a chair-back, showing my new design.

I claim—

The ornamental design for a chair-back as shown.

JOSEPH SILVERMAN.
